COMBINED ENGINE MOUNT AND IGNITION
WIRING MANIFOLD

Roderick W. Stekzel, Hohokus, N. J., assignor to
Bendix Aviation Corporation, Teterboro, N. J.,
a corporation of Delaware

Application June 7, 1948, Serial No. 31,423

3 Claims. (Cl. 248—5)

1

This invention relates to engine mounting, and ignition wiring, and particularly to a combination or unit in which an engine mount operates as a shield for the engine ignition wiring.

An object of the invention is to provide a compact, lightweight mounting for an engine, as of the radial type, which also constitutes a manifold to retain and to act as a shield for the engine ignition wires, in an arrangement which conserves space and weight where such factors are critical, as in aircraft.

Another object is to provide an engine mount, of the type indicated, which may operate in any one or combination of capacities as a radio shield, a liquid shield, and as a protective shield generally for the ignition wiring.

Another object is to provide means whereby a unit of the type indicated may be conveniently assembled and serviced, and the locating and attaching of wires facilitated.

Another object is to greatly simplify an engine and wiring assembly, not only from the standpoint of appearance, but also in the matter of rendering more accessible all parts of the engine heretofore obstructed by the wiring.

Another object is to provide a combination of the above-indicated character which is simple and durable in construction, economical to manufacture, and effective in its operation.

The above and other objects and features of the invention will appear more fully hereinafter from a consideration of the following description taken in connection with the accompanying drawings wherein one embodiment of the invention is illustrated by way of example.

In the drawings:

Figure 1 is a view, in side elevation, of a unit constructed in accordance with the invention, with the wiring shown in full lines and the mount and other parts indicated partially by full lines and partially by broken lines; and

Figure 2 is a rear elevation of the structure of Figure 1, as viewed from the right thereof, having corresponding full and broken lines.

Referring to the drawings, a combined engine mount and ignition wiring manifold 10 comprises, in the position illustrated, a frame 12 including a top tube 14 of inverted substantially U-shape, as seen in Figure 2, having a top central rear inlet opening 16. A lower tube 18, of upright substantially U-shape, cooperates with the top tube 14, as by being welded thereto at positions 20, to form an upright-plane ring-like structure 22.

Legs 24 of the top tube 14, which are substantially tangent to the ring 22, in this instance

2

extend downwardly and forwardly from the ring. A horizontal bottom tube 26 is disposed at each side of the mount extending rearwardly from the corresponding leg 24.

5 Tubes 28, as shown, extend diagonally at corresponding angles from the rear of the ring 22 adjacent to each end of the horizontal diameter of the ring to points 30 rearwardly of the ring on the corresponding horizontal side tubes 26. A rear tube 32 is disposed between, and is weld connected to, the horizontal tubes 26 adjacent to the intersections of the latter with the diagonal tubes 28. Reinforcing means or gussets 34 subtend angles between certain of the frame tubes.

10 15 Upright tubular feet 36, of less diameter than, and extending through the horizontal side tubes 26 adjacent to the front and rear ends thereof, extend for short distances above and below the side tubes 26 to act as bases for mounting bolts 20 38, Figure 1, to prevent crushing of the tubes 26 by the bolts.

25 Brackets 40, integral with the ring 22 for supporting an engine, are disposed, in this example, substantially in quadrature with each other, with one in each quarter of the ring relative to its vertical and horizontal diameters.

30 Outlet portions 42 from the ring 22 are provided one for each engine spark plug, and, as shown in this instance, are in the form of screw threaded nipples each adapted to receive an end coupling 44 of an armored flexible conduit 46. The portions 42 may, in other instances be of simple round section or bead formation to avoid sharp edges.

35 40 A box 48, secured to the ring 22 rearwardly of, and communicating with, the inlet opening 16, is provided with a rear door 50, and with flexible metal conduits 52 communicating from inner ends 53 of the conduits with, and projecting oppositely from, the ends of the box toward the sides 26 away from the ring 22. Small cylindrical terminal casings 55 are provided at outer ends 57 of the conduits 52.

An ignition circuit 54, comprising a battery 45 56, Figure 2, a solenoid 58, an ignition switch 60, and magnetos 62 and 64, also includes insulated ignition wiring 66, entirely around the ring 22 therein, having portions within conduits 68 entering the ring through the flexible conduits 52, the box 48 and the inlet 16, and portions 70 extending from the ring through the outlets 42.

55 The device, as above set forth, is radio shielded, but may also be advantageously utilized, where radio shielding is not desired, as by rounding the

outlets 42, as above indicated, and omitting parts, such as the flexible metal conduits 46, 52 and 68.

Although only one embodiment has been illustrated and described, and others sufficiently indicated, various changes in the form and relative arrangements of the parts may be made to suit requirements.

What is claimed is:

1. A combined engine mount and ignition wiring manifold, comprising, a frame including a top tube of inverted substantially U-shape having an upper inlet opening, a lower tube of upright substantially U-shape cooperating with the top tube to form an upright-plane ring-like structure the legs of the top tube being substantially tangent to the ring and extending downwardly from the ring, a horizontal bottom tube at each side of the mount extending rearwardly from the lower end of the corresponding downwardly extending leg, tubes extending diagonally from the rear of the ring adjacent to each end of the horizontal diameter of the ring to points rearwardly of the ring on the corresponding horizontal side tubes, a rear tube between and connected to the horizontal tubes adjacent to the intersections of the latter with the diagonal tubes, reinforcing means subtending angles between certain of the frame tubes, upright tubular feet extending through the horizontal side tubes adjacent to the front and rear ends thereof to positions above and below the horizontal side tubes, brackets on the ring for mounting an engine, and a plurality of outlet openings spaced along the outer circumference of said ring.

2. A combined engine mount and wiring mani-

fold, comprising, a tubular upright-plane ring having an upper inlet opening, a tubular substantially horizontal frame below and extending lengthwise forwardly from the ring plane for a given distance and rearwardly from the ring plane for a greater distance, tubular legs at each side of the mount extending forwardly and other tubular legs extending rearwardly from the ring adjacent to its horizontal median plane to the side tubes adjacent to the side tube ends, upright tubular feet extending through, above and below the side tubes adjacent to said ends, brackets on the ring for mounting an engine, and a plurality of outlet openings along the outer circumference of said ring.

3. A combined engine mount and wiring manifold, comprising, a tubular upright-plane ring having an inlet opening, a tubular substantially horizontal frame below and extending forwardly and rearwardly from the plane given distances, respectively, tubular legs extending forwardly and downwardly from the ring to the frame, brackets on the ring for mounting an engine, and an outlet from the ring for each spark plug.
